UNITED STATES PATENT OFFICE.

GEORGE W. HOPKINS, OF CLEVELAND, OHIO, ASSIGNOR TO THE ACETYLENE STOVE MANUFACTURING COMPANY, OF CLEVELAND, OHIO, A CORPORATION OF OHIO.

SAD-IRON.

1,200,496.

Specification of Letters Patent. Patented Oct. 10, 1916.

Application filed January 7, 1914. Serial No. 810,691.

To all whom it may concern:

Be it known that I, GEORGE W. HOPKINS, a citizen of the United States, residing at Cleveland, in the county of Cuyahoga and State of Ohio, have invented a certain new and useful Improvement in Sad-Irons, of which the following is a full, clear, and exact description.

This invention relates to sad irons and especially to an iron heated by a gas flame applied to the interior of the iron.

One of the main objects of the invention is to provide a sad iron whose construction admits of the continued application of an acetylene flame to the interior of the iron structure, without any danger of the gas being decomposed and causing formation and deposition of soot, or of the flame being extinguished or of flashing back into the interior of the burner.

Still further, the invention aims to provide a construction wherein the flame is so directed, distributed and controlled that it will not flash out through the openings provided along the sides of the iron, and wherein in the major portion of the heat of the flame is either applied directly to or is rapidly and effectively conducted to the base of the iron.

In general, it is the object of the invention to provide an iron which may be heated by a flame of acetylene applied to the interior of the iron, and which is efficient and satisfactory in operation.

The above and other objects which will appear in the detail description are attained by my invention, which may be briefly described as consisting in certain novel details of construction and combinations and arrangements of parts which will be described in the specification and set forth in the appended claims.

In the accompanying sheet of drawings wherein I have shown the preferred embodiment of my invention, Figure 1 is a side view of a sad iron constructed in accordance with my invention; Fig. 2 is a longitudinal sectional view of the same; Fig. 3 is a transverse sectional view substantially along the line 3-3 of Fig. 4; Fig. 4 is a top plan view with the cover of the iron removed; and Fig. 5 is a sectional view through the rear part of the sad iron and through the burner.

The sad iron constructed in accordance with my invention, is provided with a body

portion 10 of customary shape exteriorly. This body 10 which is hollow or chambered, is provided with a flat ironing or pressing base 11, and with a removable cover or top portion 12 provided with a handle 13. The top 12 which *per se* forms no part of the present invention, is composed of heat insulated lower and upper sections, and is detachably secured to the body 10 by any suitable means, which in the present case consists of interlocking parts 14 at the front end of the iron, and a clamping thumb nut 15 which engages a threaded pin 15^a on the rear end of the body and extending upwardly in a slotted or bifurcated part at the rear of the cover.

One of the principal features of the present invention resides in the arrangement of parts, and in the details of construction by which excessive heating of the burner, and consequent decomposition of the gas and extinction or flashing back of the flame into the interior of the burner is entirely avoided, even though the burner is arranged at a downward inclination, and is hence so positioned with respect to the flame that there is a natural tendency for the latter to heat the burner.

As far as I am aware, all attempts heretofore to produce a successful sad iron which is heated by an interior acetylene flame have failed, due largely to the fact that the burner is, after a very brief period of use, overheated. I believe that the failure of the prior acetylene heated sad irons is due to a great extent to a commonly accepted, but false theory, that it is essential to insulate the burner from the body of the iron to prevent overheating of the burner.

In the construction which I have provided, I avoid the overheating of the burner with its consequent serious disadvantages, regardless of the period of time that the burner or flame is in action, by a very material departure from the heretofore generally accepted theory that insulation of the burner is necessary. This I accomplish by not only avoiding the use of all insulating media between the iron and the burner, but by enhancing conduction between the iron and the burner as much as possible,—in other words, by so arranging and constructing the parts that the burner and iron are in best possible heat conducting relationship. By so doing, I secure such an ef-

fective equalization and dissipation of heat from the neighborhood of the burner that overheating of the latter is avoided. For an understanding of this important feature, 5 the construction of the burner should first be observed. The burner includes a mixing tube 17 which at its end remote from the iron is provided with an air intake chamber 18 to which will be secured a flexible gas 10 supplying tube, not shown. At its inner end, the mixing tube 17 is expanded, and has a threaded connection with an expanded mixing chamber 19 consisting of a tubular or cylindrical body provided with restricted orifices which prevent back flashing of the 15 flame into the interior of the chamber, these orifices being in the form of narrow slots 19^a which are closely arranged and extend lengthwise of the chamber 19. Screwed 20 onto the outer end of the mixing chamber 19 is a delivery cap 20 provided at its inner end with a central delivery orifice 20^a, and separated from the mixing chamber by an annular space in which further 25 commingling of air and gas takes place before the mixture passes through the delivery orifice. It will be noted that the mixing tube 17, mixing chamber 19, and delivery cap 20 have good heat conducting relationship, by 30 reason of which the heat may readily pass from one member to the other. The delivery cap 20 extends through and has a very close threaded connection with the rear wall 21 of the iron, the inner end of the delivery cap 35 being just within the wall of the iron, and the burner as a whole being inclined downwardly so that the flame which will be projected from the inner end of the delivery cap will be directed down onto the base 11 40 of the iron.

To avoid overheating of the cap, I provide good conducting relationship between the cap and the portion of the iron through 45 which the cap extends by intimately associating these parts, and by providing as much metal as possible of one in contact with the other. This is brought out by providing on the rear wall 21 an inclined boss 22 and by providing on the interior of the 50 boss and on the exterior of the delivery cap, a very close pitch thread, so that when the burner or the delivery cap of the burner is screwed into the boss and into the end wall of the iron, the major portion of the cap 55 is in direct contact with said end wall or boss, so that heat can readily pass from the delivery cap into the rear part of the iron, and so will be conducted from the delivery cap and dissipated in the parts of lower 60 temperature. I find that with this construction, neither the delivery cap nor the inner mixing chamber will become sufficiently hot 65 that the acetylene gas will decompose or flash back into the cap.

65 On the interior of the iron and above the

base 11, a short distance in advance of the orifice of the burner, I provide a baffle plate 23, which in accordance with another feature of my invention is inclined downwardly toward the front of the iron. This baffle 70 plate is provided with a number of burner openings 24 distributed over the same, and through these burner openings, the unconsumed gas, that is the gas not consumed between the base 11 and baffle 23, passes, and 75 is ignited in the form of small flames which are above the baffle. These burner openings 24 are not of uniform size, but preferably are of gradually decreasing size from the rear of the baffle to the front, four different 80 sizes of openings being here shown, there being a group of openings of each size. I find that this arrangement of openings in the baffle is preferable, as I am thus enabled to secure a more uniform distribution of 85 flame over the baffle, whereas, if the openings were of uniform size and uniformly spaced, the flame or flames at the forward end of the baffle would be much higher than those at the rear end, the natural tendency 90 for the unconsumed gas being to pass through the forward openings rather than through the rear openings. However, by varying the size or distribution of the openings, the flames can be distributed as desired, and the consequent heat can be either 95 distributed or localized as circumstances may require.

It will be understood of course that considerable heat is imparted to the baffle plate 100 both by the flame beneath and above the same. In order that as great a proportion as possible of this heat may be utilized in heating the base 10, I provide good conducting relationship between the baffle plate and the base 11 by providing along the side walls 105 of the iron and integral with the base, rather massive heat conducting shoulders 25 to which the baffle plate is suitably secured by means of screws 26, and through which the 110 heat is very readily conducted from the baffle to the base 11.

In each of the side walls of the iron, and near the base 11 are arranged a series of air intake openings 27, a large opening 28 115 being provided in each of the side walls at the rear of the heat conducting shoulders 25, and the other openings passing transversely through the conducting shoulders 25.

Preferably, the inner walls of the conducting shoulders 25 are fluted or corrugated, the indentations of the corrugations being located in line with the openings. This feature has two advantages, viz: the corrugations increase the heat absorbing capacity 125 of the conducting shoulders, and the decrease in the length of the air intake openings through the shoulders decreases the resistance to the inflow of air and consequently admits of a greater flow of air than would 130

be possible if the air were conducted through a thicker wall, assuming of course that the openings are of the same size.

In the upper part of the side walls of the iron are provided elongated vent openings 29 through which pass outwardly the products of combustion. I prefer to provide also a vent opening 30 in the front wall or apex of the iron, as I find that with a rather large vent opening provided at this point, a more desirable distribution of the flame is obtained.

With the construction above described, not only is there such a good conduction of heat away from the burner that overheating of the latter is avoided, but the construction is such that high efficiency is obtained in the respect that the major portion of the heat is applied or conducted to that part of the iron which it is desired to heat. Furthermore, the arrangement and relative sizes of the burner openings in the baffle, together with the arrangement of air intake and vent openings are such that an even distribution of flame is obtained, and there is no danger of the flame shooting out laterally through the vent openings 29.

Having thus described my invention, what I claim is:

30 1. In combination, a chambered sad iron, a burner extending through the wall of the iron, said burner comprising an inner mixing chamber provided with orifices and an outer delivery cap provided with an orifice, 35 there being a space between the mixing chamber and delivery cap, said delivery cap and the wall of the iron through which the burner extends being in close engagement for a portion of the length of the cap.

40 2. In combination, a chambered sad iron having a boss, a burner extending through the boss comprising an inner mixing chamber having a plurality of orifices and a delivery cap surrounding and spaced from the orificed part of the mixing chamber, said cap being tightly fitted in said boss.

45 3. In combination, a chambered sad iron, a gas burner extending through the rear wall of the iron, a baffle in the iron extending across the chamber and inclined downwardly from its rear end to its forward end, and at its forward end engaging the base of the iron, the said baffle having distributed openings.

55 4. In combination, a chambered sad iron, a gas burner extending through the wall of the iron, a baffle in the iron extending across the chamber and inclined downwardly from its rear end to its forward end, and at its forward end engaging the front wall of the iron adjacent the base of the latter, said baffle having distributed perforations.

5. In combination, a sad iron having an inner chamber, a gas burner extending through the wall thereof, a perforated baffle

plate inclined downwardly from its rear end to its forward end and extending across the chamber from one side wall thereof to the other, and a pair of shoulders supporting the baffle, said shoulders being continuous 70 from the rear end to the forward end of the baffle and being integral with the sides and base of the iron.

6. In combination, a sad iron having an interior chamber, a burner extending into the same, a pair of downwardly inclined shoulders arranged along the sides and integral with the sides and base of the chamber, and a downwardly inclined perforated baffle extending over and secured to said shoulders. 75

7. In combination, a chambered sad iron, a gas burner extending through the rear wall of the iron, a pair of corrugated downwardly inclined baffle supporting shoulders 85 arranged along the sides of the iron, and a downwardly inclined perforated baffle supported on said shoulders and extending from one side of the iron to the other.

8. In combination, a chambered sad iron, 90 a gas burner extending through the rear wall thereof, a baffle arranged above the base of the iron, a pair of baffle supporting shoulders along opposite sides of the iron, said shoulders having along the side walls thereof indentations and air intake openings extending through the side walls and shoulders in line with said indentations. 95

9. In combination, a chambered sad iron, 100 a gas burner extending through the rear wall of the iron and inclined downwardly toward the base of the iron, a baffle plate arranged above the base and inclined downwardly from its rear end to its front end and extending from one side of the iron to the other, shoulders arranged along the sides of the iron and extending inwardly from the sides and integral with the sides and base, said shoulders supporting said baffle plate, 105 said iron having air intake openings in its side walls beneath the baffle and adjacent the base, and having vent openings in its side walls above the baffle.

10. In combination, a chambered sad iron, 110 a burner extending through the rear wall of the iron, a baffle plate supported above the base of the iron forwardly of said burner, said baffle plate having burner openings of varying sizes.

11. In combination, a chambered sad iron, 115 a downwardly inclined gas burner extending through the rear wall of the iron, a baffle supported above the base of the iron forwardly of said burner and inclined downwardly from its rear end, said baffle being provided with distributed burner openings, the openings adjacent the forward end of the plate being smaller than the openings near the rear end of the plate. 125

12. In combination, a chambered sad iron 130

having a downwardly inclined burner extending through the rear wall thereof, a baffle arranged above the base forwardly of the burner and inclined downwardly from its rear end, said baffle being provided with distributed burner openings of gradually decreasing size from the rear to the front end, baffle supporting shoulders arranged along the side walls of the iron, said side walls being provided beneath the baffle with

air inlet openings, and said side walls and the front of the iron being provided above the baffle with vent openings.

In testimony whereof, I hereunto affix my signature in the presence of two witnesses. 15
